UNITED STATES PATENT OFFICE.

DANIEL E. MYERS, OF LONGVIEW, TEXAS.

CHILD'S BED.

1,267,260.

Specification of Letters Patent. Patented May 21, 1918.

Application filed October 12, 1917. Serial No. 196,236.

To all whom it may concern:

Be it known that I, DANIEL E. MYERS, a citizen of the United States, residing at Longview, in the county of Gregg and State 5 of Texas, have invented new and useful Improvements in Children's Beds, of which the following is a specification.

This invention is a folding crib attachment for bedsteads wherein the crib may be 10 folded and slid under an ordinary bedstead.

One object of the invention is to provide an attachment so that a crib may be slid under the ordinary bedstead when in a folded position.

15 Another object is to provide an attachment that may be removably secured to the bed in a strong and rigid manner which will permit of easy withdrawal of the crib when it is desired to utilize the crib for resting purposes.

20 The invention, broadly stated, comprises a folding crib that is adapted to slide beneath a bedstead in coöperation with suitable ways or guides suspended from the side 25 rails of the bedstead, the head and foot ends of the crib being foldable through rotation around fixed points, which ends are operatively connected together by means of rods or bars, side rails for supporting a mattress and springs which are also operatively 30 connected with the ends so that upon withdrawal of the crib from beneath the bedstead, the rails are simultaneously raised which serves to move the mattress where its top 35 will lie in substantially the same plane as the top of the bedstead mattress, and locking means to retain the crib in its withdrawn position when the ends are raised to the vertical plane.

40 One practical form of construction and assembly will be described and illustrated in the accompanying drawings, in which—

Figure 1 is a perspective view with the crib withdrawn from beneath the bedstead.

45 Fig. 2 is a side elevation of the withdrawn crib showing the connecting rods or bars and the latch, with head and foot ends or boards raised in a vertical plane.

Fig. 3 is a side elevation with the head and 50 foot ends or boards of the crib depressed and showing the crib placed under the bed, and

Fig. 4 is a vertical sectional view through the bedstead and crib on the line 4—4 of Fig. 2.

In the preferred embodiment better to be 55 described, the bedstead A may be provided with the usual head board or end 6 and the foot board or end 7. The side rails 8 and 9 may be of the usual type or construction, and as shown in the drawings are of L-shape, 60 which shape is customarily employed in the ordinary forms of metal bedsteads.

The rail 8 may be provided adjacent its ends with the curved hangers 10, and the rail 9 may be provided with straight hangers 65 indicated at 12. The hangers are preferably disposed in such a manner that the guide and support members 14 and 15, which they support will lie between and at right angles to the side rails 8 and 9.

70 It is preferred to connect the hangers 11 and 13 by means of the guide and support member 14 and the hangers 10 and 12 with the guide and support member 15. By doing so a rigid construction is formed that is 75 simple in assembly. As shown, in the several figures, one pair of hangers are preferably curved. The reason therefor will be more fully described hereafter. The guide and support members 14 and 15 are pref- 80 erably tubular so that they may accommodate the small tubes or rods 16 and 17, which tubes serve also to provide a pivotal connection for the foot board or end 18 and the head board or end 19 of the crib when in co- 85 operation with the guide and support members 14 and 15.

86 In order to provide a removable connection for the attachment with an ordinary bedstead, the hangers 10 and 12 may be provided with suitable ends that are adapted to engage with the side rails by means of suitable screws 20. The side rail may be securely clamped in the hanger, or in other words the hanger may be firmly attached to 95 the rail. The foot and head boards 18 and 19 of the crib may have their posts 21 similarly formed. As shown, the external posts are preferably flat and where they connect with the rods 16 and 17 they are provided with 100 an inclined portion as indicated at 22.

The connecting rods 25 and 26 connect the two outer posts 21 together. As shown in Fig. 2, the rod 26 is pivoted to the right hand post 21 above the point where said post is 105 pivoted to the tube 16 and with the lower end of the left hand post and the rod 25 is reversely arranged. Thus it will be seen

that the rods 25 and 26 are crossed in order that the head and foot ends may swing toward each other.

Each inner post indicated at 21^a is also provided with an inclined portion and an L-shaped portion indicated at 27. These inner posts are provided with this L-shaped portion which, in one sense, serves as an offset so that when the head and foot boards are raised to the vertical plane they will clear the side rail 8. These posts 21^a are also provided with the circular sections 28 each of which has a hole therein of sufficient size to permit them to slide upon the guide and support members 14 and 15.

Upon each of the guide members 14 and 15 there may be provided the stop collars 29. In each of the posts 21 and 21^a there is provided a series of holes, which may be indicated at 30. These holes preferably extend transversely of the straight portions of the posts. These holes 30 serve to provide a pivotal connection for the curve members 31 whose lower ends are connected with the side rail 32 of the crib.

The action of these curve members 31 which serve as supports for the crib side rails 32 will be more clearly seen in Figs 2 and 3 where the crib is shown withdrawn from beneath the bed and which is also shown as being disposed or placed underneath in a folded position.

As the head and foot boards are raised to vertical position they carry with it these curved members 31 and thereby pull upward the side rails. These side rails also serve to support the springs 33 and the mattress 34. It is desired to make these curved supporting members 31 of such shape and length that when the head and foot boards are raised, the top of the mattress 34 will lie in the same plane as the mattress 35 of the regular bed, though by reason of the holes 30 said mattress may be placed in any desired position. If desired, the outer curved members 31 may be provided with suitable notches or teeth, indicated at 36, and a pawl 37 may be operatively connected to each post. The pawl may be so positioned with reference to the teeth 36 that upon raising the foot board, as illustrated in Fig. 2, this pawl will drop into the teeth and prevent an untimely folding of the crib. As shown, this arrangement will provide a suitable locking and retaining means for the crib in its withdrawn and adjusted position.

In practical use, when it is desired to withdraw the crib from beneath the bed, the posts 21 may be employed as handles to pull it out. The rods or tubes 16 and 17 then slide from within the guide and support members 14 and 15 and the circular portions 28 slide upon the exterior of these members 14 and 15. By this means a good and sub-

stantial support is provided which makes for ease of operation.

When the crib has been fully withdrawn, the head and foot ends are raised or lifted from their contact with the mattress 34 which raising will move the curved supporting members 31, thus raising the side rails 32. When the posts 21 and 21^a arrive at their extreme vertical position, the top of the mattress 34 will then be in substantially the same horizontal plane as the top of the mattress 35.

In order to provide for a simultaneous movement of both the head and foot ends, the connecting rods or bars 25 and 26 are employed and they are so connected to the posts that a pull upon either head or foot board will serve to move the opposite board in the same relative position as the board operated upon. As these boards reach the end of their travel in the upward direction the pawl 37 will engage with the teeth 36 formed on the curve member 31 and tend to prevent the crib from returning to its folded position. In order to provide for a more complete closure of the external side or length of the crib when withdrawn from beneath the bedstead, the side B may be employed. This may be solid or of the same design as the head and foot boards. It may also be formed of two members C and D pivotally connected with the posts 21 and also be provided with suitable locking means. These doors or closures C and D may be adapted to fold inwardly against their respective ends or boards 18 and 19.

When it is desired to move the crib to its position beneath the bed, the closures C and D are unlatched and folded against their respective ends. The pawls 37 are disconnected and the boards or ends 18 and 19 are moved around their pivoted connection on the rods 16 and 17 so that they tend to lie upon the top of the mattress 34. In doing so, the curve members 31 by means of their pivotal connections with the posts of the crib, serve to lower the side rails 32 and therefore the springs 33 and mattress 34. The crib when so folded is adapted to pass beneath the side rails of the bed with sufficient clearance and the side rails 32 of the crib clear the floor.

At no time does this attachment interfere with the use or occupancy of the bed, either in its operative or inoperative position.

What I claim is:—

1. The combination with a bedstead, of hangers connected thereto, guiding and supporting members connected to the hangers, a slideable crib having pivotally mounted head and foot boards operatively connected with the side rails, said latter connection serving to raise and lower the crib when changed from its operative to inoperative

position, and means to automatically retain the boards in a raised position.

2. A crib attachment for bedsteads comprising hangers secured thereto, guide and support members connected to the hangers and extending transversely of the bedstead, a crib provided with coöperative members connecting head and foot boards with its

side rails, side boards having a pivotal connection with the guide and support to permit of the raising and lowering of the side rails of the crib, means serving to lock the boards in a raised position and a swingable closure for the external side of the crib.

In testimony whereof I affix my signature. 15
DANIEL E. MYERS.

Copies of this patent may be obtained for five cents each, by addressing the "Commissioner of Patents, Washington, D. C."
